US0D1068195S

(12) **United States Design Patent** (10) **Patent No.:** **US D1,068,195 S**
(45) **Date of Patent:** **** Mar. 25, 2025**

(54) **SILICONE PAD**

(71) Applicant: **JIANGSU ESONE NEW MATERIAL CO., LTD**, Taizhou (CN)

(72) Inventor: **Yongxiang Xiong**, Taizhou (CN)

(73) Assignee: **JIANGSU ESONE NEW MATERIAL CO., LTD**, Taizhou (CN)

(**) Term: **15 Years**

(21) Appl. No.: **29/977,210**

(22) Filed: **Dec. 6, 2024**

(51) LOC (15) Cl. **07-05**

(52) U.S. Cl.

USPC **D32/55**

(58) **Field of Classification Search**

(57) **CLAIM**

The ornamental design for a silicone pad, as shown and described.

DESCRIPTION

FIG. 1 is a front perspective view of a silicone pad, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The dash-dot-dash broken lines encircling the enlarged views are for annotative purposes only and form no part of the claim thereof.

1 Claim, 9 Drawing Sheets
